UNITED STATES PATENT OFFICE.

WILLIAM R. WHITE, OF NOGAL, TERRITORY OF NEW MEXICO.

SKIRT-SUPPORTER.

No. 843,782.

Specification of Letters Patent.

Patented Feb. 12, 1907.

Application filed July 2, 1906. Serial No. 324,444.

To all whom it may concern:

Be it known that I, WILLIAM R. WHITE, citizen of the United States, residing at Nogal, in the county of Lincoln and Territory of New Mexico, have invented certain new and useful Improvements in Skirt-Supporters, of which the following is a specification.

This invention consists of novel means for supporting skirts of ladies or misses and attaching the same to the waist in such a way as to obviate likelihood of the skirt-band being pulled downwardly or disconnected from the waist in any way.

For a full understanding of the invention and the merits thereof and also to acquire a knowledge of the details of construction of the means for effecting the result reference is to be had to the following description and accompanying drawings, in which—

Figure 1 is a perspective view showing the invention applied. Fig. 2 is a horizontal sectional view. Fig. 3 is a detail view of the coöperating plates which are attached to the belts. Fig. 4 is a vertical sectional view through the parts comprising the invention.

Corresponding and like parts are referred to in the following description and indicated in all the views of the drawings by the same reference characters.

Specifically describing the invention, the numeral 1 designates the waist worn by the person using the supporter, and the numeral 2 the skirt part. The supporter consists of the inner belt 3 and the outer belt 4, as above specified, and these belts are preferably composed of double-ply material and may be made of cloth, leather, or the like. The rear portions of each of the belts 3 and 4 are reinforced by means of plates 5 and 6, respectively. Each of the plates 5 and 6 is received between the plies of material comprising the belt to which it is secured, and the plate 5 is formed with projections 7, extending from its outer side and adapted to extend into or through slots 8, formed in the plate 6, applied to the outer belt.

The plates 5 and 6 may be of any suitable length and preferably extend about from hip to hip and across the back of the body of the wearer. The inner belt will of course be se-

cured at the front by a suitable buckle composed of parts attached to the ends of said belt. In like manner the outer belt will have a buckle to secure its ends at the front, and this buckle may be of any ornamental type desired or otherwise.

In the actual use of the invention the inner belt 3 is secured about the waist of the wearer beneath the dress-waist. When the skirt has been adjusted properly, the outer belt is next placed in position and extends about the waistband of the skirt, so that when it is buckled the projections 7 on the plate 5 force the waist material, as well as the skirt-band material, slightly outward through the slots 8 in the plate 6 of the outer belt 4. An interlocking connection is thus virtually established between the belts 3 and 4, and the material from which the skirt-band and waist is made is very firmly connected with the belt parts in an evident manner.

The manner of applying the plates 5 and 6 to the belts, to which they are attached, is extremely advantageous by reason of the fact that said plates are housed or inclosed by the fabric or like material from which the belts are made. The plates 5 and 6, and especially the plate 5, are not likely to rust and soil those portions of the wearing-apparel with which they come into contact. Furthermore, the inclosing of the plates in the belt parts prevents the projections 7 from likelihood of tearing the material with which they engage.

Having thus described the invention, what is claimed as new is—

A skirt-supporter comprising inner and outer belts, each belt consisting of double-ply material, a reinforcing-plate received between the plies of each belt, the plate of the outer belt being provided with slots or openings in its length, while the plate of the inner belt is formed with projections in its length adapted to enter the slots or openings in the plate of the outer belt.

In testimony whereof I affix my signature in presence of two witnesses.

WILLIAM R. WHITE. [L. s.]
